UNITED STATES PATENT OFFICE

WILLIAM D. POMEROY, OF SENECA FALLS, NEW YORK, ASSIGNOR TO GOULDS PUMPS INCORPORATED, OF SENECA FALLS, NEW YORK, A CORPORATION OF NEW YORK

CAR-WASHING APPARATUS

Application filed July 27, 1927. Serial No. 208,807.

This invention relates to certain new and useful improvements in washing apparatus, and more specifically to an apparatus for spraying fluid upon automobiles, altho capable of use for various and many purposes.

In car washers or outfits for spraying fluid upon cars or for other similar purposes, high pressures, as for instance 300 pounds, are required, and it is found that no ordinary spray outfit is capable of standing up very long under the strain of such pressures, or of satisfactory use in producing the result sought.

Further, it is quite essential that the pressure should be maintained substantially uniform at the desired point, irrespective of whether the spraying device or devices are being used or not, and that so far as possible, extreme pressure surges should be avoided in the system.

Further, in prior devices, it has been customary to use a pump from which the volume discharge is quite uniform, varying not more than about 22 per cent during each cycle of movement, and with such a pump the operation of the regulator valve used has been unsatisfactory for the reason that with a pump having a very uniform discharge, the regulator valve will raise slightly off its seat when the required pressure exists in the system and will permit a portion of the discharge from the pump to continuously by-pass back to the intake of the pump and a condition of substantial equilibrium will exist in the system.

This continuous by-passing of a portion of the fluid from the pump gives a very high velocity discharge between the regulator valve and its seat, which cuts out the valve and its seat very rapidly, and further, the full load is maintained on the motor driving the pump, with the result that excess power has been used and the operative life of the apparatus has been brief.

I have discovered that by the use of a single cylinder double acting pump in which the volume of discharge varies substantially during each cycle, as for instance a variation ranging from 0 to 132 per cent, as illustrated in Figure 6, that a regulator valve can be constructed for use with such a pump which will open suddenly and fully taking

the entire discharge from the pump and relieving most of the pressure in the system and permitting the pump to merely circulate the fluid until such time as the pressure conditions controlling the regulator valve change to permit sudden and complete closing of such valve.

A further object resides in the provision of a structure in which the regulator valve cuts in and cuts out at comparatively infrequent intervals so that the apparatus will not chatter itself to pieces during a comparatively short period of use.

A further object and advantage resides in the provision of a regulator cushioning chamber preferably adjacent the pump to substantially eliminate excess pressure conditions resulting in the system from rapid acceleration of fluid when the by-pass valve closes suddenly, and to cushion the operation of said valve.

The combination of elements at present deemed essential to accomplish the advantages above described, and other advantages that will hereinafter appear from the following description, involves primarily a single cylinder double-acting pump discharging into an air chamber having very considerable capacity as compared to the discharge of the pump per cycle with a check valve to prevent flow of fluid back into the pump cylinder combined with a by-pass and valve controlling the same so proportioned as to open suddenly and fully, taking the entire discharge of the pump, and at the same time relieving most of the pressure in the system back of the check valve controlling the discharge air or cushioning chamber, and an auxiliary air chamber for cushioning the operation of the regulator valve and for taking care of any excess pressure conditions that would result from sudden closing of the regulator valve.

Other objects and advantages relate to the details of the structure, and the form, relation and association of the parts thereof, all as will more fully appear from the following description, taken in connection with the accompanying drawings in which:

Figure 1 is an elevation of an apparatus of this invention.

Figure 2 is a top plan view of the apparatus illustrating portions in section.

Figure 3 is a section on line 3—3, Figure 2.

Figure 4 is a section on line 4—4, Figure 2, but showing the regulator cushioning chamber in full lines.

Figure 5 is a section on line 5—5, Figure 2, but showing the regulator cushioning chamber and regulator valve in section.

Figure 6 is a chart illustrative of the volume discharge for each cycle from a single cylinder double acting pump as herein disclosed.

The apparatus as here illustrated comprises a single cylinder double-acting pump, perhaps best shown and illustrated in Figure 3. The cylinder —1— of this pump opens at opposite ends into the water ways or pump chambers —2— and —3— respectively, each of these chambers being provided with an inlet valve —4— and an outlet valve —5—. These valves may be of the composition disk type, and are normally held to their seats by springs, as shown, the springs being properly tensioned to effect the desired function.

The inlet pipe or conduit —6—, Fig. 1, which may be connected to any suitable source of fluid, as for instance, a water main, discharges into the inlet manifold —7—, Fig. 3, for supplying fluid thru the passageways controlled by valves —4— to the respective water-ways or chambers —2— and —3—, and upon the pressure strokes of the piston —8— mounted in cylinder —1—, the fluid is alternately forced under pressure through the passageways controlled by the outlet valves —5— into an outlet manifold —9— connected by pipe or conduit —10— leading through a passageway —11—, Fig. 5, to the base of a discharge cushioning or air chamber 12 through a passageway 13 controlled by valve 14 normally held by spring 15 to its seat, and operating to prevent the return of fluid from the discharge air chamber 12 to the outlet side of the pump.

The discharge air-chamber 12 is of very considerable capacity as compared with the capacity of the pump per cycle of operation, and it is desirable to maintain a considerable air pressure in the chamber 12 to effect the desired cushioning result, and for that purpose a pipe 16, Fig. 5, may penetrate the wall of the air chamber and may lead to any source of air under pressure as controlled by a valve 17, gauge 18 being provided for indicating pressure. The piston 8, Fig. 3, is reciprocated through the medium of a piston rod 19 extending outwardly through a stuffing box 20 and gland 21 secured thereto, the stuffing box and gland forming a fluid-tight joint to prevent the escape of fluid from the pump along the piston-rod 19.

A yoke 22 is secured to the outer end of the piston rod and is connected at its opposite

ends to side rods 23 and 24, Fig. 2, disposed upon opposite sides of the pump and extending substantially parallel with the piston-rod 19, the opposite ends of these side rods 23 and 24 connected respectively to a cross-head consisting of the parts numbered 25, 26, Fig. 3, the part 26 being guided in cylinder 27, such cross-head being actuated by a connecting rod —28— mounted upon a bearing —29— eccentric with respect to gear —30— for reciprocating piston —26— as the gear is rotated.

Gear —30— may be driven from a smaller gear —31— which in turn is driven by a pulley —32—, Fig. 2, the pulley being driven as by belt —33— from a second or smaller pulley —34— mounted on the armature shaft —35—, Fig. 1, of an electric motor —36—.

It will be apparent that as motor —36— is driven, the piston —8—, Fig. 3, will be reciprocated by movement of parts described to alternately draw in and expel fluid to and from the respective water-ways or chambers —2— and —3—, and that the fluid under pressure will pass from the manifold —9—, Fig. 5, by the opening valve —14— into the discharge cushioning chamber —12— to produce the desired pressure.

In order that such pressure may be maintained under varying conditions of discharge from the chamber —12— through tubes or hose connections —37—, Fig. 1, connected to pipe —38—, Fig. 5, through which the passage of fluid is controlled as by valve —39—, Fig. 2, to spray nozzle or nozzles —40—, Fig. 1, and in order that continuous operation of the pump will not produce an excess pressure in the system beyond that desired, a regulator is provided adapted to be actuated by and in accordance with the pressure existing in the cushioning chamber —12—, and this regulator includes a chamber —41—, Fig. 5, connected as by pipe —42— to the lower portion of the discharge cushioning chamber —12— so that substantially the same pressure will exist in chamber —41— as exists in the chamber —12—.

One wall, as here shown, the upper wall of chamber —41— includes a flexible diaphragm —42— backed by a slidible member or piston —43—. A valve-operating rod —44— is connected to the piston —43— and at its upper end loosely engages a valve —45— controlling the passage of fluid from the manifold —9— through pipe —46—, chamber —47—, to a pipe —48— leading, in this instance to the suction line —6— which returns the fluid to the manifold —7— of the pump.

When valve —45— is pushed upwardly from its seat so as to completely open the passageway from manifold —9— to pipe —48—, it will be apparent that the fluid may flow directly from the outlet or pressure side of the pump to the inlet or suction side of the pump, under which circumstances the

pump is merely circulating the fluid without the production of any substantial pressure in the system.

5 Valve 45 is normally held to its seat by means of spring 49, which spring is confined between the upper side of the valve and the lower end of a regulator cushioning or air chamber 50, which cushioning or air chamber is at all times in communication 10 with the outlet side or manifold 9 of the pump. The piston 43 and valve rod 44 are normally maintained in the position shown in Figure 5 (with valve 45 closed by spring 49) through the medium 15 of a coil spring 51 confined between the upper surface of the piston 43 and the lower surface of a stop disk 52 secured in any suitable and preferably adjustable manner to properly tension the spring 51 20 as by means of bolts 53 secured to the wall of the chamber 41, and which chamber is supported as for instance by integral brackets 54, Fig. 4, depending from a casting which includes the chamber 47 25 and the passageway leading to the pipe 48.

When the suction line 6 is connected to a source of fluid under pressure, as for instance a city water line, a cushioning chamber 55 is provided which may be in the form of an elongated cylinder connected at its lower end by pipe 56 to the manifold 7 to absorb shocks and to tend to maintain a uniform pressure in the fluid supplied to 35 the inlet side of the pump.

The operation of the regulator of this apparatus will be understood from the following:

40 Figure 6 is a chart showing the volume discharge from the pump herein disclosed and is given so that the new and different way in which my apparatus functions and the reason therefore can be better understood. The type of pump herein disclosed has during 45 each revolution an average discharge indicated on the chart as 100% but during each revolution the volume of discharge varies from 0 to about 132 per cent of the average volume discharge as indicated on the 50 chart and this maximum discharge takes place twice during each revolution as hereininafter explained. This variation of volume discharge has a very important bearing on the functioning of my structure and in order 55 to have a structure which will properly function it is essential that a pump having a wide variation in volume discharge be used.

When the apparatus is in operation valve 45, Fig. 5, remains closed until a desired 60 pressure is built up within the discharge cushioning chamber 12. At that time the built-up pressure in chamber 12 also exists in chamber 41 and this pressure exerted upon the diaphragm 42 and piston 43 must be greater than the sum of

the pressures of springs 49 and 51 plus the pressure on top of the valve 45, or else the valve would not open, and for that reason the pressure of the springs is so adjusted as to permit opening of valve 45 at the desired fluid pressure.

When sufficient pressure is built up in the entire system so that the pressure in chamber 41 becomes great enough to overcome the forces opposing the opening of valve 45, the valve 45 will be raised off its seat to a slight extent, and as soon as the rotation of the pump reaches a point such as A in Figure 6 where substantially all discharge from the pump ceases momentarily, and there is substantially no pressure on top of valve 45, the check valve 14, preventing the return of any pressure from chamber 12, the valve 45 will snap wide open, due to the fact that under such circumstances the pressure in chamber 41 becomes substantially greater than the forces opposing it, and valve 45 will remain wide open, permitting by-passing of substantially the entire capacity of the pump until pressure in air chamber 12 drops to such a point that the pressure in chamber 41 is less than the forces tending to close valve 45, at which time valve 45 will start to close.

If the pump used had a fairly constant discharge, it would tend to build up a condition of equilibrium in the system between the forces tending to open valve 45 and those tending to close it, and the valve would stay partially open, allowing a portion of the discharge from the pump to by-pass and a condition of equilibrium would be reached, but with the variable volume discharge pump here disclosed, the volume discharge of which is illustrated in Figure 6, it is apparent that at points B in each cycle of operation, a very considerable extra volume of water is being discharged from the space between valve 45 and its seat, and will build up a momentary increased pressure on top of valve 45, and this increases the force tending to close valve 45 to such a point that the valve snaps closed suddenly.

With sudden closing of the valve 45, an excess pressure condition would be built up in the system due to the fact that there is a considerable mass of stationary water in the pipes connecting between the pump and air chamber 12, and this water would have to be very suddenly accelerated were it not for the provision of cushioning chamber 50, and the inclusion of such a regulator cushioning chamber is essential to the satisfactory operation of the structure herein disclosed, and with a regulator valve operating as disclosed, and upon sudden closing of valve 45, injurious excess pressure conditions are not built up in the system for the reason that chamber 50 constitutes a space for receiving excess

fluid, such space being made available by the compression of air in chamber —50—.

The by-pass valve —45— must be so proportioned that there is a proper relation between the forces tending to open the valve and those tending to close it within the range in which it is desired to maintain pressure in the discharge air chamber —12—.

It is not only desirable, but quite essential that the regulator valve shall operate at as infrequent intervals as possible, and the fact that the air chamber —12— is very large as compared to the capacity of the pump per cycle has a substantial bearing on the frequency of operation of the regulator valve, and this for the reason that the greater volume of air under compression in the air chamber, the longer will be the period of charge or discharge of the air chamber with the maintenance of pressure within given limits.

The apparatus herein illustrated is of comparatively rigid and permanent construction, substantially automatic in operation, compact in form and arrangement, efficient in operation and in the consumption of energy for effecting such operation, and altho I have shown and described specific details of a perhaps preferred installation, together with the particular design and relation of the parts thereof, I do not desire to restrict myself to the details of form, construction, or arrangement, as various changes and modifications may be made within the scope of the appended claims.

I claim:

1. An apparatus of the class described comprising a pump, a discharge air chamber having an inlet in communication with the pump and having a capacity many times the volume of fluid discharged by the pump at each cycle of operation, a valve controlling such inlet, said discharge air chamber having an outlet separate from the said inlet, a by-pass conduit in communication with the pump outlet, a regulator valve controlling the passage of fluid through said conduit, means actuated in accordance with the pressure of fluid in the discharge air chamber for opening said regulator valve to permit bypassing of fluid, and a cushioning air chamber in communication with said by-pass conduit at a point adjacent the pump outlet, and opening downwardly above the regulator valve.

2. An apparatus of the class described comprising a pump, a discharge air chamber having a capacity many times the volume of fluid discharged by the pump at each cycle of operation, a conduit leading from the pump outlet to the discharge air chamber, a valve controlling communication between said conduit and the discharge air chamber, said discharge air chamber having an outlet separate from its valve controlled inlet, a

by-pass conduit in communication with the pump outlet, a regulator valve structure including a valve controlling the passage of fluid through said by-pass conduit, a fluid chamber having a movable wall adapted to actuate said valve, a separate conduit connecting the discharge air chamber with the said regulator valve chamber, and a cushioning air chamber in communication with said by-pass conduit at a point between said valve and the pump outlet.

In witness whereof I have hereunto set my hand and seal this twenty-first day of July, 1927.

WILLIAM D. POMEROY.
